(57) **CLAIM**

The ornamental design for a protective batting glove, as shown and described.

DESCRIPTION

FIG. 1 is a front perspective view of a protective batting glove.

FIG. 2 is a front elevational view of a protective batting glove.

FIG. 3 is a rear elevational view of a protective batting glove.

FIG. 4 is a right side elevational view of a protective batting glove.

FIG. 5 is a left side elevational view of a protective batting glove.

FIG. 6 is a top plan view of a protective batting glove; and, FIG. 7 is a bottom plan view of a protective batting glove. The broken lines shown in FIGS. 1-7 are included for the purpose of illustrating environmental elements only and form no part of the claimed design.

1 Claim, 6 Drawing Sheets
